REED AND BACKSTAY ADJUSTMENT FOR LOOMS

Elbridge R. Holmes, Worcester, Mass., assignor to Crompton & Knowles Loom Works, Worcester, Mass., a corporation of Massachusetts

Application June 11, 1931. Serial No. 543,625

20 Claims. (Cl. 139—189)

This invention relates to improvements in mountings for loom reeds and it is the general object of the invention to provide means whereby a reed may be given various setting transversely and longitudinally of the lay.

It is another object of my present invention to provide the reed with a mounting slidably connected to the lay so that the reed as a whole may move parallel to the lay to accommodate slight variations in the direction of feed of the warp and cloth. This sliding connection may preferably though not necessarily take the form of a pivotal connection between the reed and the lay, in which case the reed can move both transversely and longitudinally of the lay to accommodate various conditions arising in the operation of the loom.

Loom reeds are ordinarily carried in a fixed position with respect to the lay but their constant beating against the fell of the cloth wears the reed wires, necessitating a change of vertical position in order to prevent cutting of the filling. It is a further object of my invention to provide improved means to vary the position of the reed relatively to the cloth line of the loom.

The cloth line is determined to some extent by a warp engaging rod, preferably of glass, and it is another object of my invention to be able to adjust this rod relatively to the reed.

It is a still further object of my invention to provide an adjustable positioner for the lower rib of the reed to be located on the lay by positioning elements, such as screws, to determine the relation of the reed relatively to the lay.

It is another object of my invention to provide means for holding the top of the reed adjustably against a surface which may be parallel to or extend at least longitudinally of the lay to permit vertical adjustments of the reed.

With these and other objects in view which will appear as the description proceeds, my invention resides in the combination and arrangement of parts hereinafter described and set forth in the claims.

In the accompanying drawing, wherein a convenient embodiment of my invention is set forth, Fig. 1 is a vertical transverse section through a lay made according to my present invention.

Fig. 2 is a front elevation of the structure shown in Fig. 1 and showing the reed in one adjusted position.

Fig. 3 is a diagrammatic view similar to a part of Fig. 1 on a reduced scale showing the reed in two adjusted positions vertically.

Fig. 4 is a diagrammatic view taken from the

back of the loom and showing the reed in three different positions transversely of the cloth, and

Fig. 5 is a detail horizontal section on line 5—5 of Fig. 2.

Referring to the drawing, I have shown a lay 10 supported by lay swords one of which is indicated at 11 in Fig. 2. The lay may be made of a wooden beam or the like and has on the top thereof of the customary race plate 12 of the shuttle. At each end of the lay is a lay end 13 having an upwardly extending horn 14. Each of the latter supports a foot 15 of a bearing 16 and the foot is provided with slots 17 through which extend bolts 18 threaded into the arm 14. The bearing is therefore adjusted vertically to assume a plurality of positions with respect to the race plate and lay 12.

The bearing 16 supports a stud 20 which projects toward the center of the loom and has slidably and rotatably mounted thereon a pivot element 21. The latter is connected by bolts 22 as shown in Fig. 2 to a hand rail section 23 formed T-shape as shown in Fig. 1. The top of this section supports a wooden hand hold 24, while the lower end is formed as a vertical web 25. A retaining plate 26 has a horizontal foot 27 held against the web 25 by screws 28, the lower end of the plate forcing the top rib 29 of the reed R against the section 25. By varying the position of the rib 29 relatively to the parts 25 and 26 the reed can be raised or lowered with respect to the hand rail and also the stud 20. A further vertical adjustment of the reed may be secured by manipulating the nuts 18, the slots 17 permitting movement of the top structure as a whole relatively to the lay.

The rear upper edge of the lay is notched as at 30, having vertical and horizontal walls 31 and 32, respectively. Horizontal positioning screws 33 pass through the lay wood and project somewhat beyond the vertical wall 31, being held by rear and front nuts 34 and 35, respectively. A reed positioner 36 L-shape in section has a vertical web 37 which engages the positioning screws 33, while the horizontal part 38 is slotted and receives a tightening or clamping bolt 39. The latter is tightened with respect to the lay so as to hold the reed positioner in rigid position with respect to the lay. The reed has a lower rib 40 forward movement of which is limited by the web 37.

The backstay 45 carries a glass rod 46 and bears against the rib 40, being supported on at least two levers 47 one of which is shown in Figs. 1 and 2. Each of these levers has at the

lower end thereof a hub 48 which pivots around a stud 49 carried by a bracket 50. The latter extends upwardly and has slot 51 through which extend securing bolts 52. The latter are held by a depending support 53 secured to the under side of the lay. The support is provided with an ear 54 which extends substantially parallel to a similar ear 55 formed on the lever 47. A bolt 56 extends through the ears and has at the rear end thereof a head 57 bearing against the ear 55 under pressure of a compression spring 58 which is interposed between the ear 54 and lock nuts 59 on the bolt.

The pivot element 21 has two relatively large holes 65 through which the bolts 22 pass. This enables the top of the reed to be moved toward or from the lay front, depending upon the direction of adjustment of the positioner 37.

The backstay can be moved vertically with respect to the lay by adjusting the bolts 52 and it will be seen that the ears 54 and 55 both move together, so that an adjustment of the bracket 50 moves the lever 47, ear 54, and the bolt 56, thereby preserving this part of the structure in proper relation for its various adjusted positions.

As shown in Fig. 3, the hand rail and reed are shown in relatively low position in full lines and in adjusted raised position in dotted lines, indicating the manner of changing the point at which the beat-up occurs on the reed. Fig. 4 shows the reed in the central position with respect to the loom in full lines, the dotted lines 60 at the right indicating that the reed as a whole can move to the right along the studs 20, while the dotted lines 70 at the left indicate the opposite movement of the reed.

From the foregoing it will be seen that I have provided means for giving the reed a variety of movements both vertically and longitudinally of the lay. It will also be seen that I have provided means for conveniently varying the vertical position of the glass rod 46 and also preserve the yielding connection between the lever 47 and the bracket 50. In this connection it is to be understood that spring 58 resists rearward movement of the backstay. Furthermore, the reed can move parallel to the lay against the sliding resistance of spring 58.

Having thus described my invention it will be seen that changes and modifications may be made therein by those skilled in the art without departing from the spirit and scope of the invention and I do not wish to be limited to the details herein disclosed, but what I claim is:

1. In a loom having a lay, a reed, a supporting structure for the reed having detachable holding relation with the reed and capable of relative adjustment with respect to the reed longitudinally of the lay, and sliding connections between the reed structure and lay extending in a direction parallel to the lay, the reed and structure responsive on any pick of the loom to move longitudinally of the lay in either direction by forces transmitted through the warp.

2. In a loom having a lay, a reed, and means defining pivotal and sliding connections between the reed and lay, said connections having coacting surfaces extending parallel to the lay, the reed and means responsive on any pick of the loom to move longitudinally of the lay in either direction by forces transmitted through the warp.

3. In a loom having a lay, a reed, and means interposed between the reed and lay to mount the reed on the lay for free movement parallel to the lay, the reed and means responsive on any pick

of the loom to move longitudinally of the lay in either direction by forces transmitted through the warp.

4. In a loom having a lay movable toward and from the fell of the cloth, a reed, a reed supporting structure, and means defining a pivotal and sliding connection between the lay and structure to render the reed movable at any time along the lay by forces exerted by the warp parallel to the lay, said means to move the reed and structure as a unit to different positions relatively to the lay and transversely of the plane of the cloth, said means extending parallel to the lay and the structure being slidable by reason of said means in a direction parallel to the plane of the cloth.

5. In a loom, a lay, a reed, supporting structure for the top of the reed, yielding means to position the bottom of the reed, and sliding connections between the structure and lay parallel to the latter to render the reed movable at any time along the lay by forces exerted by the warp parallel to the lay.

6. In a loom, a lay, a reed, supporting structure for the top of the reed constituting the support for the reed against gravity, yielding means independent of the supporting structure to position the bottom of the reed, and sliding connections between the structure and lay parallel to the latter to render the reed movable at any time along the lay by forces exerted by the warp parallel to the lay, the yielding means exerting a force transversely of the lay, and the reed being slidable relatively to the yielding means in a direction parallel to the lay.

7. In a loom, a lay, a reed, supporting structure for the top of the reed, yielding means to position the bottom of the reed, and sliding connections between the structure and lay parallel to the latter to render the reed movable at any time along the lay by forces exerted by the warp parallel to the lay, the yielding means exerting a force transversely of the lay, and the reed being movable with the cloth as the latter undergoes slight changes of position parallel to the lay.

8. In a loom, a lay, a reed, supporting structure for the top of the reed, sliding connections between the structure and lay parallel to the latter to render the reed movable at any time along the lay by forces exerted by the warp parallel to the lay, and means to alter the position of the connections in a direction transverse of the lay.

9. In a loom, a lay, a reed, supporting structure to support the reed from the top thereof, sliding connections between the structure and lay parallel to the latter, and means to alter the position of the connections in a direction transverse of the cloth.

10. In a loom, a lay, a reed supported on the lay from a point above the cloth, a backstay for the reed, a support depending from the lay, a bracket secured to the support in adjusted vertical position, and a lever pivoted to the bracket and having supporting relation with the backstay and movable with the bracket vertically independent of the reed.

11. In a loom, a lay, a reed supported on the lay from a point above the cloth, a backstay for the reed, a support depending from the lay, a bracket secured to the support in adjusted vertical position, a lever pivoted to the bracket and having supporting relation with the backstay and movable with the bracket vertically independent of the reed, and yielding connections carried by and interposed between the bracket and lever.

12. In a loom, a lay, a reed supported on the

- lay from a point above the cloth, a backstay for the reed, a support depending from the lay, a bracket secured to the support in adjusted vertical position, a lever pivoted to the bracket and having supporting relation with the backstay and movable with the bracket vertically independent of the reed, and yielding connections carried by and interposed between the bracket and lever, said connections including a rigid element passing through parts of the bracket and lever. 5 80
13. In a loom, a lay, a reed supported on the lay from a point above the cloth, a backstay for the reed, a support depending from the lay, a bracket secured to the support in adjusted vertical position, and a connection between the bracket and backstay to cause the bracket and connection to move together vertically, independently of the reed. 15 85
14. In a loom having a lay movable forwardly toward the fell of the cloth, a pivotal support on the lay above the cloth, a reed supporting structure above the cloth mounted to move about said pivotal support, said structure having a member T-shaped in cross section with a vertical web, a reed, and means to clamp a portion of the reed against the vertical web in any one of a plurality of vertical positions. 20 90
15. In a loom having a lay movable forwardly toward the fell of the cloth, means defining a pair 30 95
- 35 of spaced substantially parallel vertical surfaces one above and the other below the fell of the cloth, a reed having top and bottom ribs, means to clamp the top rib against the surface above the fell and thereby support the reed from above the fell, and a yieldable backstay to hold the lower rib against the lower surfaces, said reed ribs capable of assuming any one of a plurality of vertical positions relatively to their respective surfaces. 40 100
16. In a loom, a lay, a reed, a reed supporting structure having a vertical surface, means to clamp the top of the reed against said surface in any one of several vertical positions relatively to the structure and thereby support the reed from above the cloth, and means to secure the structure to the lay in any one of several vertical positions relatively to the lay. 105
17. In a loom, a lay, a reed supported on the lay from a point above the fell of the cloth, a backstay for the reed, a support depending from the lay, a bracket secured to the support in adjusted vertical position and bearing against the reed below the fell, a lever pivoted to the bracket and having supporting relation with the backstay, and a warp supporting rod extending longitudinally of the lay and supported by the backstay. 110
18. In a loom, a lay, a reed, a backstay, a warp supporting rod on the backstay to engage and position the warp to determine the position of the cloth relatively to the reed, supporting means for the reed above the cloth to hold the reed in fixed position relatively to the lay, and means to vary the position of the backstay and rod relatively to the reed independently of the supporting means to change the relation of the cloth and reed. 115
19. In a loom, a lay, a reed, supporting structure for the reed, and sliding connections between the structure and lay lying outside the cloth space, said structure being responsive to strains parallel to the lay and exerted by the warp at any time during the weaving operation. 120
20. In a loom having a lay, a reed supported against gravity from a point above the cloth, a backstay supported from a point below the cloth, a warp support mounted on the backstay, and means to hold the backstay and support in any one of a plurality of positions with respect to and independently of the reed. 125
